UNITED STATES PATENT OFFICE

2,586,317

UNITARY DEVICE FOR SELECTIVELY ACTUATING MULTIPLE TRIGGERS

Walter M. Fay, Ludlow, Mass.

Application March 8, 1950, Serial No. 148,390

1 Claim. (Cl. 42—42)

1

My invention relates to firearms and is directed more particularly to a unitary device for securement to the trigger guard of a plural triggered firearm for selectively actuating the triggers of a firearm.

The principal objects of my invention are directed to the provision of a unitary device for attaching to a trigger guard which includes a relatively few parts and is constructed and arranged for selectively engaging the triggers of a firearm and for actuating the same.

All of the above objects I accomplish by means of such structure and relative arrangement of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed in the claim hereunto annexed and more fully described and referred to in connection with the accompanying drawing wherein:

Fig. 1 is a front elevational view of the trigger actuating device of the invention which is shown as being secured to a trigger guard;

Fig. 2 is a plan view of the trigger actuating device of my invention;

Figs. 3 and 4 are end and front elevational views respectively of the lever of the device shown in Figs. 1 and 2;

Fig. 5 is an end elevational view of the selector of the device shown in Figs. 1 and 2;

Fig. 6 is a rear elevational view of the rear trigger actuator; and

Figs. 7 and 8 are each diagrammatic views to illustrate the operation of the selector and actuator.

Referring now to the drawing more in detail, the invention will be fully described.

A portion 2 of a frame of a firearm, such as a shot gun, has a trigger guard 4 secured thereto and depending therefrom.

Forward and rear triggers 6 and 8 depend from the frame. When the gun is cocked, either trigger may be moved rearwardly or to the left, as shown in Fig. 1, for the discharge of the arm.

A support includes a foot 10 which is secured to the lower portion of the trigger guard 4 and has an upwardly extending left plate portion 12. The foot 10 may be secured to the guard 4 by screws 14 or the like.

A lever 16, shown in Figs. 3 and 4, is U-shaped

2

in cross section, and is swingable on a screw 20' which is fixed to the left plate 12.

A selector 20 has spaced left and right parts 22 and 24 outside the lever 16 which are pivoted at 26 to the said lever 16.

A guide 28 is fixed to the left plate 12 and extends to the right therefrom. The rear end of the selector 20 is provided with an opening 30 in which the guide 28 is disposed and a pilot 32 of said selector extends into said opening 30.

A trigger actuator 36 is swingable on a pivot 38 extending to the right from the rear plate 12 and has on its rear end a trigger engaging lug 40.

The left side of the trigger actuator 36 is provided with a notch 42 and a prong 44, as is shown in Fig. 6.

A stop 46 is fixed to and extends to the right from the left plate 12 and is receivable in the notch 42 of the trigger actuator 36 so as to limit 20 movement of the actuator in rearwardly counterclockwise swinging.

A spring 48 around the screw 20' has an upper end 50 against a retainer 52 which extends to the right from the plate 12 and a lower end 54 against a lower portion of the lever 16. This spring 48 functions to urge the lever 16 counterclockwise. The lever 16 in turn urges the selector 20 forwardly so that the rear side of the opening 30 therein abuts the member 28, as in Fig. 1.

30 A trigger member has a right plate 56 secured to the right part 24 of the selector 20 by screws 58 and a transverse curved finger engaging part 60. A trigger actuator 62 extends rearwardly from the finger engaging part 60.

35 With the right plate 56 of the trigger member secured to part 24 of the selector said trigger member is swingable on pivotal connection 26.

The parts are so arranged and the device is so secured to the trigger guard that the member 62 lies just forwardly of the trigger 6 while the part 40 of actuator 36 lies just forwardly of the trigger 8.

40 Either trigger may be actuated, or they may be actuated successively in the order desired.

45 To actuate the trigger 6 with the trigger finger forwardly of part 60, pressure is applied thereto in such a way as to swing the selector counterclockwise and rearwardly. The pilot 32 of the selector engages the lower portion of guide 28 which guides the selector in counterclockwise and rearward movement. The shoulder 64 of the selector passes by prong 44 of the member 36, as shown in Fig. 8.

50 In the cocked position of the firearm triggers, 55 the prong 44 and the shoulder are in spaced relation as in Fig. 1.

When trigger 8 is to be actuated, part 60 is

engaged by the trigger finger and pressed so as to swing the selector clockwise and move it rearwardly. In this movement member 62 moves clockwise and downwardly and away from trigger 6, pilot 32 rides along rearwardly on guide 28 and shoulder 64 engages prong 44 of actuator 36 to swing it clockwise so the part 40 thereof acts on trigger.

The parts will be so arranged and disposed relative to the triggers that the triggers will not be actuated until the pilot 32 has advanced to and engaged the guide 28 according to the trigger to be actuated, that is, until the parts are engaged for guiding the selector in a certain path, either up or down.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the appended claim are therefore intended to be embraced therein.

What it is desired to claim and secure by Letters Patent of the United States is:

A trigger operating mechanism for securement to the trigger guard of a firearm having separate forward and rear triggers within said guard comprising in combination, a support having a horizontal foot portion for securement to a trigger guard and a left plate portion extending vertically upwardly from a left longitudinal edge thereof, a guide fixed to and extending outwardly to the right from said plate portion adjacent a rear end thereof being in cross section of greater length horizontally than of vertical thickness and having upper and lower sides converging forwardly, an elongated selector having forward and rear ends and extending generally horizon-

tally at the right of the plate portion of said support, pivotal connections between the rear end of said selector and said plate portion for substantially horizontal swinging movements of said actuator forward and back between forward cocked position and rear firing positions of said triggers and for up and down tilting movements of the rear and forward ends of said actuator in back and forth movements thereof, the rear end of said selector provided with an opening loosely surrounding said guide and having a rearwardly directed pilot extending from the forward side of said opening for engaging and traversing the upper or lower side of said guide for guiding the opposite ends of the selector up or down as it is swung rearwardly, means for urging said selector forwardly, a rear trigger actuator pivoted to said left plate adapted to be swung forwardly by a rear trigger and a stop carried by said left plate engageable by said actuator to limit forward movements thereof, a forward trigger actuator secured to said selector having a finger engaging portion for disposition forwardly of a forward trigger and a trigger member for engaging a forward trigger, said selector and rear trigger actuator provided with operable engageable means, all adapted and arranged whereby the finger engaging portion of the forward trigger actuator may be tilted up or down and moved rearwardly so that a forward trigger is operated by said trigger member or the rear trigger is operated by said rear trigger actuator through the engaging means of said selector and rear trigger actuator.
